UNITED STATES PATENT OFFICE.

MADISON D. SHIPMAN, OF DE KALB, ILLINOIS.

BUTTON.

SPECIFICATION forming part of Letters Patent No. 350,776, dated October 12, 1886.

Application filed November 23, 1885. Serial No. 183,769. (No model.)

To all whom it may concern:

Be it known that I, MADISON D. SHIPMAN, a citizen of the United States, residing at De Kalb, in the county of De Kalb and State of Illinois, have invented certain new and useful Improvements in Buttons, of which the following is a specification, reference being had thereto to the accompanying drawings, in which—

10 Figure 1 is a central vertical section of the head of my improved button attached to the fabric. Fig. 2 is a similar view of the flanged tube thereof, detached. Fig. 3 is a similar view of a modified form of cap, showing also its flanged tube detached. Fig. 4 is a similar 15 view of the cap provided with my unlocking device. Fig. 5 is a plan view of the unlocking-lever. Fig. 6 is a side view of the same. Fig. 7 is a sectional view of the stud. Fig. 8 20 is a plan view of the washer used for securing the stud to the fabric. Fig. 9 is a vertical section of a solid stud.

This invention relates to separable buttons; and it consists in the peculiar combinations 25 and the novel construction and arrangement of parts, all as more fully hereinafter described and claimed.

In the drawings, A designates the cap, preferably of the form shown. B is the stud-receiving tube, provided with a base, b, corrugated, as shown, so as to form a ridge, b', for a purpose soon to be explained. C is an eyelet of ordinary construction. These parts, together with the spring D, (hereinafter described,) constitute the head of the button, which is attached to the fabric in the following manner: The cap A and tube B are first united by turning the edge a of the cap A under the edge of the base b of the tube, leaving 30 a recess, a', between the base of the tube and the inturned edge of the cap, as seen in Fig. 1. These parts are then placed upon the fabric and the eyelet put through from the other side, and when the parts are pressed together the end of the eyelet, striking against the ridge b' of the corrugated base of the tube, is deflected or turned outward under the base of the tube into the recess a', above referred to, formed between the base of the tube and 45 the edge of the cap, thus firmly uniting the parts and securing the head to the fabric. The tube B within the cap is formed with a hori-

zontal slot, b². D is the spring above referred to. It is a spiral spring surrounding the tube B, with its end passed through and resting in 55 the slot b².

Instead of using the form of tube illustrated in Figs. 1 and 2, I sometimes prefer to use the form shown in Fig. 3, in which the base b is turned under to form a recess, c, and a ridge, 60 d, into which recess the end of the eyelet passes when spread out by striking against the ridge d. When I use this form of tube, I do not turn in the end of the cap, as in Figs. 1 and 2; but said end is just turned under the edge of the 55 flange of the base, which, it will be noticed, is rounded sufficiently to hold the two parts together, as clearly shown in Fig. 3.

The stud E, which may be either solid or hollow, as preferred, is formed with a round 70 head, e, a flange, e', and a notch or groove, e². This stud is put through the fabric, and when made hollow is secured thereto in the following manner: G is a washer, having a central opening, g, which is a little smaller than the 75 stud E. At the center this washer is slit at two or more places, as shown in Fig. 8. This washer is slipped on over the stud, as shown in Fig. 7, the slit portions yielding sufficiently to allow of the passage of the stud. When the 80 outer edge of the washer comes in contact with the fabric, pressure on the slit portions will cause them to contract and assume their normal position, forcing or pressing in the metal of the tube, and the edges of the slit 85 portions entering the depression made in the tube prevent the separation of the parts.

When a solid stud is used, it is provided with an annular groove or depression, h, to receive the edge of the slit portions of the 90 washer, which is the same as that used with the hollow stud, and is applied in the same way, it being of course understood that the slit portions of the washer spring into the groove in the stud when they are coincident 95 therewith. I preferably, though not necessarily, press or bend up the slit portions of the washer, as shown in Fig. 7, so as to slightly increase the size of the central opening, so that it can more readily and easily be slipped 100 over the stud. This is desirable when used with a hollow stud, but not when a solid stud is used.

When it is desired to connect the two parts

of the button, the stud is inserted in the tube B of the head, the round head of the stud readily passing by and pressing outward the spring within the slot in the tube until the groove in 5 the stud is coincident with said slot, when the spring falls into the groove in the stud and secures the two parts of the button together. The two parts may be separated by a sudden pull on either the head or the stud, or by pulling 10 both in opposite directions; but I prefer to use, more especially when I employ a stud having a straight-sided recess, as shown in Fig. 9, what I term "an unlocking device," which consists, preferably, of a piece of sheet 15 metal, I, formed in the shape shown in Fig. 5, and provided with a hand-piece, i, and two arms or bifurcations, i' i'. Each of the arms of this lever is provided with a spur or projection, j, inclined, as shown in Fig. 6. In 20 Fig. 4 this device is shown in position. Its hand-piece i projects through a slot, A', in the cap A, while its arms i' i' straddle or extend one on each side of the tube B, so as to leave a free passage for the stud. The spurs j engage 25 the end of the spring D that is in the slot in the tube. When the stud and head are connected with the spring engaging the groove in the stud, and it is desired to disengage or separate the same, it is only necessary to press 30 in upon the lever I, when the spurs j, engaging the spring D, force the same out of the slot in the tube B, and consequently out of engagement with the groove in the stud, when the latter is free to be removed.

35 While I have shown and described what at the present time I consider the preferable form of unlocking device, I do not wish to confine myself to that particular construction, as it is evident that the same may be varied to some 40 extent without departing from the spirit of my invention.

When it is desirable, as it sometimes will be, to use the two parts of the button in eyelet-holes, the eyelet C, used for securing the head 45 to the fabric, and the washer G, for securing the stud, may be omitted and the edge of the cap turned in against the base of the tube B, as shown in dotted lines in Fig. 4.

What I claim as new is—

50 1. The combination, in a separable button, of the cap A, the perforated tube B, and the spiral spring having its upper end coiled around and closely embracing said tube and its end entering the perforation therein, with 55 a stud having a notch or groove adapted to receive the end of said spring, substantially as described.

2. The combination, in a separable button, of a cap, A, a fastener, as C, and a tube, B,

inclosed in said cap, with its apex extending 60 toward the top of said cap, and having a base adapted to deflect the fastener when the two are forced together, substantially as described.

3. The combination, in a separable button, 65 of a cap, A, a perforated tube inclosed in said cap and having corrugated base b, provided with the inturned flange, and a fastener, as C, adapted to expand into the recess in the base, substantially as described.

4. The combination, in a separable button, 70 of a fastener, as C, a tube, B, having a base the inner part of which is inclined upward and adapted to deflect the fastener when the two are forced together, and a cap constructed to inclose the tube and the deflected end of the 75 fastener, substantially as described.

5. The combination, with an apertured tube, 80 a spring encircling said tube with its end resting in the aperture therein, and a notched stud adapted to engage with said spring, of an unlocking device, substantially as described, for disengaging said spring from the stud, substantially as described.

6. The combination, with an apertured tube, 85 a spring encircling the same with its end resting in the aperture therein, and a notched stud adapted to engage with said spring, of a bifurcated unlocking-plate adapted to disengage the spring from the stud, substantially as described. 90

7. The combination, with a separable button having a notched stud and a spring catching into the same, of a bifurcated plate having spurs or projections adapted to disengage the spring from the stud, substantially as and for 95 the purpose specified.

8. The combination, in a separable button, and as a means of securing one member thereof to the material, of a hollow stud and a slit washer having a central aperture, and the slit 100 portion raised and adapted to be closed around said stud by pressure, substantially as described.

9. The process of permanently securing a portion of one member of a button to another 105 portion thereof, which consists in inserting said portion through a washer having its central portion raised, and then closing the inner edges of the washer around the inserted part by forcibly flattening the washer, substantially 110 as described.

In testimony whereof I affix my signature, in presence of two witnesses, this 21st day of November, 1885.

MADISON D. SHIPMAN.
